F. T. SNYDER.
CONTACT FOR ELECTRIC FURNACES.
APPLICATION FILED OCT. 28, 1912.

1,100,993.

Patented June 23, 1914.

UNITED STATES PATENT OFFICE.

FREDERICK T. SNYDER, OF OAK PARK, ILLINOIS.

CONTACT FOR ELECTRIC FURNACES.

1,100,993.

Specification of Letters Patent. Patented June 23, 1914.

Application filed October 28, 1912. Serial No. 728,088.

To all whom it may concern:

Be it known that I, FREDERICK T. SNYDER, citizen of the United States, residing at Oak Park, in the county of Cook and State 5 of Illinois, have invented a certain new and useful Improvement in Contacts for Electric Furnaces, of which the following is a full, clear, concise, and exact description.

My invention relates to electric furnaces, 10 and more particularly to the bottom electrode or contact-holder of an electric furnace. Its object is to provide an electrode or contact-holder which can be readily secured to the exterior casing or shell of the 15 furnace, which will provide good electrical connection between the electrode and the ground connection therefor and suitable means for cooling the electrode.

In a well known type of electric furnace, 20 the negative electrode extends vertically through the cover of the furnace, the bottom of the furnace being provided with an opening for receiving the bottom or positive electrode or contact, which latter may consist in part of the molten material treated 25 in the furnace, the lower end of the bottom electrode or contact extending through the wall of the furnace and being held in place and cooled in some suitable manner.

30 It is the object of my invention to provide improved means for cooling the contact or bottom electrode of an electric furnace of the type described.

My invention may be more readily understood 35 by reference to the accompanying drawings, in which—

Figure 1 is a central, vertical section of 40 an electric furnace embodying my invention; Fig. 2 is an enlarged elevation, partly in section, of the contact shown in Fig. 1; Fig. 3 is an elevation at right angles to the elevation shown in Fig. 2; and Fig. 4 is a top plan view of the contact.

Similar reference characters refer to similar 45 parts throughout the several views.

Referring to the drawings, the lower wall or bottom of the furnace is of the usual construction, comprising masonry 1 inclosed by a metallic shell or casing 2, preferably of 50 copper, said wall or bottom of the furnace being provided with an opening for the reception of the contact 3. Mounted upon the bottom of the furnace about said opening and detachably secured to the shell 2 is the 55 contact-holder 4. Said contact-holder and contact are preferably cast in one integral

piece. The contact-holder is preferably a metallic block having six rectangular faces. At its four corners the block 4 is provided with vertical holes 5 for the reception of 60 bolts 6, whereby the holder may be bolted to the wall of the furnace and, by tightening the nuts 7, may be drawn into close contact with the shell 2. The block 4 and the contact proper 3 is preferably a steel casting. 65 By bolting the holder 4 to the shell 2, good electric contact is provided between said shell and contact-holder. Heretofore it has been customary to ground the holder by a flexible conductor secured thereto. In the 70 preferred embodiment of my invention, as shown in the drawings, the flexible ground connection 8 is clamped by the plate 9, or in any suitable manner, to the shell 2 near the circumference thereof. The flexible conductor 10 is thus connected to the shell 2 at a readily accessible portion thereof. When the electrode is in position the ground connection for the material in the furnace extends through the contact 3, the holder 4, 75 the metallic shell 2 and the flexible conductor 8.

The block 4 is formed with one or more water chambers 10, through which water is circulated for cooling the block 4 and contact 3. Said chambers 10 are of circular cross-section and the circular walls thereof are spirally grooved so as to give a whirling motion to the water as it is circulated through the chambers, and also to increase 80 the inner surface of the chamber with which the water comes into rubbing contact. Since the transfer conductivity of heat from metal to water varies directly as the velocity of the water, it is desirable that 85 the velocity of the water be as high as practicable. By this is not meant merely the velocity of the water as it passes through the inlet port or out of the outlet port. Such rapid circulation of the water would 90 be inefficient and costly. My invention, on the contrary, is designed to give to a comparatively slow flowing stream of water a relatively high rubbing velocity with the walls of the water-chamber and thus to get 95 the most efficient cooling from a minimum volume of water. The water-chambers 10 are preferably straight holes extending from one side to the other of the block 4. These 100 holes are cored through said block, and the outer ends thereof are preferably of reduced diameter and are threaded to receive the 110

inlet pipes 11, 11 and the outlet pipes 12, 12. Said pipes are thus connected directly to the block 4 without the provision of any intermediate coupling member.

5 My invention thus provides a simple, cheap and efficient water-cooled bottom-electrode or contact.

I claim:—

1. A contact-holder having a water-chamber provided with means for imparting a whirling motion to water circulated through said chamber.

2. A contact-holder having a spirally grooved water-chamber.

15 3. A contact-holder comprising a metallic block provided with a hole extending therethrough constituting a water-chamber, the block being threaded at the opposite ends of said hole to receive a correspondingly

threaded inlet and an outlet pipe, respectively, and the main portion of said chamber being provided with a continuous groove extending spirally about said chamber. 20

4. In an electric furnace, a contact having an enlarged lower end provided with a 25 spirally grooved water-chamber.

5. In an electric furnace, a contact having an enlarged lower end provided with a 30 spirally grooved water-chamber of circular cross-section.

In witness whereof, I hereunto subscribe my name this 26th day of October, A. D. 1912.

FREDERICK T. SNYDER.
